(57) **CLAIM**

The ornamental design for an animal water dispenser, as shown and described.

DESCRIPTION

FIG. 1 is a top perspective view of an animal water dispenser showing my new design, the broken lines are for illustrative purposes only and form no part of the claimed design; FIG. 2 is a top perspective view thereof, showing the opposite side of FIG. 1;

FIG. 3 is a top plan view thereof;

FIG. 4 is a side elevational view thereof;

FIG. 5 is a side elevational view thereof, opposite of FIG. 4;

FIG. 6 is a bottom plan view thereof;

FIG. 7 is an end elevational view thereof; and,

FIG. 8 is an end elevational view thereof, opposite of FIG. 7.
